UNITED STATES PATENT OFFICE

ANDREW DEMCAK, OF TWO RIVERS, WISCONSIN, ASSIGNOR TO HAMILTON MANUFACTURING COMPANY, OF TWO RIVERS, WISCONSIN, A CORPORATION OF WISCONSIN

DESIGN FOR A FURNITURE LEG OR SIMILAR ARTICLE

Application filed April 22, 1932. Serial No. 43,572. Term of patent 7 years.

To all whom it may concern:

Be it known that I, ANDREW DEMCAK, a citizen of the United States, residing at Two Rivers, in the county of Manitowoc, State of Wisconsin, have invented a new, original, and ornamental Design for a Furniture Leg or Similar Article, of which the following is a specification, reference being had to the accompanying drawing, forming part thereof.

In the drawing, Figure 1 is an elevational view of a furniture leg or similar article, embodying my new design; and Figure 2 is a bottom plan view of the leg of Figure 1.

I claim:

The ornamental design for a furniture leg or similar article, substantially as shown.

In witness whereof, I hereunto subscribe my name.

ANDREW DEMCAK.
